UNITED STATES PATENT OFFICE.

WILLIAM H. C. BINGHAM, OF NEW YORK, N. Y., ASSIGNOR TO LAVINIA BINGHAM, OF NEW YORK, N. Y.

PERMANENT-HAIR-WAVING DEVICE AND THE LIKE AND METHOD OF USING SAME.

Application filed November 23, 1927. Serial No. 235,193.

This invention relates to improvements in permanent hair waving devices and has particular reference to a device of the type wherein in two pivotally connected members are utilized to engage and wave the hair therebetween.

An object of the invention is to provide an improved device of simple and practical construction which will effectively and quickly 10 wave the hair by the application of heat and pressure.

Another object is to mount a heating element in one of the members constituting the device in such manner that when a strand of 15 hair is engaged between the members a pressure element normally positioned in the other member may be moved into contact with said strand and force the same into a waved condition in proximity to said heating element.

20 A further object is to form the two pivoted members of the device so that when they are brought together with a strand of hair therebetween they will combine to form a chamber in which the heat from a heating element 25 within one of the members and the steam generated by the application of the heat to the moistened strand will be retained.

The above and other objects will appear more clearly from the following description 30 when taken in connection with the accompanying drawing, in which

Figure 1 is a side elevation of the device partly broken away and showing the clamping members in closed position.

35 Figure 2 is a similar view illustrating the device in its operative position; and

Figure 3 is a section taken on the line 3—3 of Figure 1.

Figure 4 is a section taken on the line 3—3 40 of Figure 1.

The preferred embodiment of the inventive idea, as shown in the drawing, comprises the cooperating clamping members 5 and 6 made of suitable material such as aluminum and pivoted at the inner ends, as indicated at 45 7, with the member 5 provided with a shank 8 carrying the handle 9 of insulated material while the member 6 has an extension 10 forming a handle portion.

50 The members 5 and 6 are both arcuate in cross section and the longitudinal edges thereof are formed with outwardly extending flanges 11 which engage and retain a strand of hair between the same when the members 55 are in operative or clamping position, said

strand extending transversely of the members and normally in the plane between the opposed flanges thereof. The member 5 is formed with a partition 12 of the same general configuration as the member itself which provides a compartment in which is mounted an electric heating element 13 of any well known construction, said partition providing a bearing surface against which the portion of the strand of hair held between the opposite pairs of flanges 11 is forced so as to be brought into intimate contact therewith, in a manner which will presently appear. The heating element 13 is connected, by suitable conductors 14, to a thermostatically controlled element conventionally shown at 15 in the handle 9 and which is, in turn, joined to a source of current supply.

Previous to engaging a strand between the members 5 and 6, as above described, the hair is moistened. To form the wave, there is provided a pressure lever 16 also movable about the point 7 and having a rod portion 17, circular in cross section, extending longitudinally of the interior of the member 6, the end of said portion being adjacent to said point. The rod portion is normally held within the confines of the member 6, by the retractile spring 18 connecting the extension 10 with the lever 16. However, after the members have been brought together, as shown in Figure 1, by movement about the pivot 7, a further movement of the lever 16 toward the handle 9 and relative to the extension 10 will expand the spring 18 and force the rod 17 from the position shown in Figure 2 to its operated position in Figure 1. In so doing, the portion of the strand of hair held between the members 5 and 6 will be slightly stretched and forced into the member 5 and in contact with the partition 12 which has been heated by the element 13.

The hair being moist, steam will be generated by this contact and the steam will be confined to a large extent in the chamber joined by the member 6 which is now closed by reason of the members 5 and 6 having been brought together. Thus through the combination of the application of heat to the hair and the confinement of the steam within the clamping members, it is necessary to hold each strand of hair between the members for only a comparatively short time before the hair is formed into what is commonly known as a permanent wave.

To release the strand from the device, pres-

sure upon the lever 16 is first relieved, whereupon the spring 18 will act to restore the rod 17 to its normally retracted position within the member 6 after which the members 5 and 6 are separated.

Other modifications and changes may be made without departing from the scope of my invention as my device may also be constructed so that various kinds of clamping and other devices may be added to the fulcrum thereby aiding in stretching the hair and keeping hair in position between chambers 5 and 6. Chamber 5 may also be constructed so as to have asbestos or any other heat resisting material cover the inside surface of 5 thus retaining the heat and making the device safer to use.

Point 7 is so constructed with a fulcrum movement that when pressure is applied to member 16 the pressure of 17 is evenly distributed on hair clamped between chambers 5 and 6 at point 11. Flange 11 may also be so constructed as to have rough surfaces or corrugations so as to keep strands of hair in position.

The present method of producing what is known as a permanent wave constitutes a lengthy process, namely, the hair in all cases is shampooed and dried then divided off into from thirty-five to fifty sections or parts, each part or section is then tied with a string and wound around small rods and again tied with strings. After this procedure flannel strips or what is known as pads or sachets which are chemically treated are after being chemically treated and wetted wrapped around each individual rod, then aluminum heaters are placed around the rods. There being one heater for each rod. Then the hair is subjected to from nine to twenty-five minutes heat. There is the risk of scalp burns due to the fact that no control can be kept over the amount of liquid contained in flannel strips, pad or sachets. The system of today takes from one and a half to three hours to produce what is known as a permanent wave and also greatly inconveniences the person by having the weight during the steaming process of from thirty-five to fifty hot heaters on the head.

My new process eliminates all the above inconveniences and in conjunction with the iron already described, produces what is known as a permanent wave in the following manner:—the hair is washed to eliminate excess oil and grease and a portion of the hair is taken and clamped in my device between chambers 5 and 6 and is stretched by rod 17 as shown in Figures 3 and 4, and steamed in one operation as aforementioned. During the stretching period the hair is dried by the heating device and forms what is known as a permanent wave. This operation can be completed in a fraction of the time now used, and at no time during the operation is the person subjected to any danger from burns or scalding

lotions or hair discoloring chemicals. The hair can also be stretched by having a stretching rod with a horizontal or rotary movement.

What is claimed is:

1. A hair waving device comprising a pair of connected clamping members connected by means of a fulcrum and adapted to engage a strand of hair therebetween, a heating element mounted in one of said members, and means within the other member movable from a normal position therein into the first named member and thereby engageable with said strand to force the same by pressure into close proximity to said heating element, said clamping members combining, when in clamping position, to form a chamber for confining therein the vapors generated by said heating element.

2. A hair waving device comprising connected clamping members connected by means of a fulcrum and adapted to engage a strand of hair therebetween, a heating element mounted in one of said members, a partition enclosing said heating element, and means within the other member movable from a normal position therein into the first named member and thereby engageable with said strand to stretch and force the same into intimate contact with said partition, said clamping members combining to form a chamber in which are confined the vapors created by contact of the hair with said partition.

3. A hair waving device comprising connected clamping members connected by means of a fulcrum and adapted to engage a strand of hair therebetween, a heating element within one of said members, a pressure rod extending into the other member and movable about the first of said members, and means to move said rod into engagement with said strand to force the same by pressure into close proximity to said heating element.

4. A hair waving device comprising connected clamping members, connected by means of a fulcrum having opposed longitudinal flanges adapted to engage a strand of hair therebetween, a heating element in one of said members, a partition forming an enclosure for said element, a rod having a normal position within the other clamping member and movable therefrom to force said strand into engagement with said partition, and means for moving said rod.

5. A hair waving device comprising connected clamping members, connected by means of a fulcrum having opposed longitudinal flanges adapted to engage a strand of hair therebetween, a heating element in one of said members, a partition forming an enclosure for said element, a rod having a normal position within the other clamping member and movable therefrom to force said strand into engagement with said partition, and means for moving said rod, and a retrac-

tile spring connecting the last named means with said other clamping member for restoring said rod to its normal position.

6. A hair waving device comprising connected clamping members connected by means of a fulcrum of arcuate formation in cross section and combining, when brought together, to form a heat and vapor retaining chamber, a heating element in one of said members, an arcuate partition forming a cover for said heating element and heated thereby, and a rod movable about the first of said clamping members to engage a strand of hair held between said members to force a portion of said strand into contact with said partition.

7. The method of producing what is commonly known as a permanent wave in hair which consists in wetting the hair and inserting same in a pair of connected clamping members connected by means of a fulcrum adapted to engage a strand of hair therebetween, a heating element mounted in one of said members, and means within the other member movable from a normal position therein into the first named member and thereby engageable with said strand to force the same by pressure into close proximity to said heating element, said clamping members combining, when in clamping position, to form a chamber for confining therein the vapors generated by said heating element, and applying heat to said heating element,

said heat being regulated by a thermostat or such other heat regulator.

8. The method of making permanent waves in hair which consists in wetting the hair and inserting same in a hair waving device comprising connected clamping members connected by means of a fulcrum adapted to engage a strand of hair therebetween, a heating element mounted in one of said members, a partition enclosing said heating element, and means within the other member movable from a normal position therein into the first named member and thereby engageable, with said strand to stretch and force the same into intimate contact with said partition.

9. The method of making permanent waves in hair which consists in wetting the hair and inserting the strand of hair in a hair waving device comprising connected clamping members, connected by means of a fulcrum having opposed longitudinal flanges adapted to engage a strand of hair therebetween, a heating element in one of said members, a partition forming an enclosure for said element, a rod having a normal position within the other clamping member and movable therefrom to force said strand into engagement with said partition, and means for moving said rod.

Signed at New York city, in the county of New York and State of New York, this 9th day of November, A. D. 1927.

WILLIAM H. C. BINGHAM.
